TEXTILE TREATING APPARATUS
Emil J. Berger and Howard K. West, Lansdale, Pa.,
assignors to Turbo Machine Company, Lansdale, Pa.,
a corporation of Pennsylvania
Filed Apr. 23, 1963, Ser. No. 274,958
10 Claims. (Cl. 68—5)

This invention relates generally to apparatus for treating textiles and particularly to apparatus for treating textile articles, such as hosiery, sweaters and the like, knitted from thermoplastic yarn, such as nylon, while stretched upon flat profile shaping forms.

A principal object of the invention is to provide an autoclave wherein textile articles may be treated with heated fluid media with an auxiliary chamber wherein treated articles may be dried and with means for conveying the articles in batches successively from the autoclave to the auxiliary chamber for drying of each batch in the auxiliary chamber while the next following batch is being treated in the autoclave.

Another object is to provide such apparatus wherein the autoclave and auxiliary chamber are closely associated in a compact unit together with means for automatically conveying batches of the articles progressively from a load-unload station to the autoclave and then to the auxiliary chamber and back to the load-unload station.

Other objects of the invention will become apparent when the following description is read with reference to the accompanying drawings, in which:

FIGURE 1 is a front elevation of apparatus constructed in accordance with the invention;

FIGURES 2, 4 and 5 are side elevations of the apparatus;

FIGURE 3 is an enlarged horizontal section on line III—III in FIGURE 1;

FIGURE 6 is an enlarged fragmentary plan view of the load-unload track section showing the carriage thereon in expanded condition;

FIGURE 7 is a vertical section on line VII—VII in FIGURE 6;

FIGURES 8, 9 and 10 are enlarged perspective views disclosing certain details;

FIGURE 11 is a horizontal section showing the door of the autoclave open and a track section carried thereby in turn carrying a carriage which is latched against expansion;

FIGURES 12 and 13 are vertical sections respectively on lines XII—XII and XIII—XIII in FIGURE 11;

FIGURE 14 is a horizontal section showing the door of the autoclave closed and a track section carried thereby in turn carrying a carriage which is not latched against expansion;

FIGURES 15 and 17 are vertical sections respectively on lines XV—XV and XVII—XVII in FIGURE 14;

FIGURE 16 is a vertical section on line XVI—XVI in FIGURE 15;

FIGURE 18 is an enlarged vertical section on line XVIII—XVIII in FIGURE 3; and

FIGURES 19 through 23 are diagrammatic figures illustrating the manner in which the carriages are shifted from track section to track section.

Broadly, apparatus embodying the invention comprises (1) an autoclave equipped with means for treating textile materials with fluid media, and (2) conveying means for loading the autoclave with work and removing the same therefrom.

Basically, the autoclave and its associated means for treating textile materials as aforesaid are the same as illustrated and described in the copending application of Emil J. Berger and Howard K. West, Serial No. 57,098, filed August 29, 1960, now Patent No. 3,131,840 of May

2

5, 1964. However, it is not intended to be limited by the treating liquid supply and distribution facilities disclosed in said copending application since these facilities may take various other forms. Even the autoclave per se may take various other forms, but the type of door with which the autoclave is equipped is preferred, if not essential, the desideratum being an upright door that is mounted for movement from its fully closed position bodily outwardly from the autoclave and back again while being held always substantially parallel to the closed position thereof.

Referring particularly to FIGURES 1, 2 and 3, the autoclave per se, generally designated 10, has a retractable door 12 at the front thereof hung from trolleys 14 which travel back and forth upon track bars 16 extending forwardly from the top of the autoclave. When closed, door 12 is held fluid-tight by retractable latches 18 against strip packing 20 disposed perimetrical about the opening of autoclave 10. Through rack and pinion means, designated 22, the door 12 is moved to opened and closed positions by a reversible electric motor 24 and an associated speed reduction unit 26 mounted atop the autoclave 10. It is believed that a more detailed description of the autoclave 10 and the associated means for treating the textile materials is unnecessary for a full understanding of the invention. However, reference may be had to the aforementioned copending application and the patents referred to therein for a fuller description.

The inventive concept involves the provision of an auxiliary chamber in which the textile materials may be dried after they are removed from the autoclave or main treatment chamber 10 and the provision of means for conveniently conveying the work from a load-unload station to the main treatment chamber 10 and through the auxiliary chamber back to the load-unload station for recirculation. Thus, it will be apparent that essentially the invention involves a novel auxiliary chamber and conveyor in combination with an autoclave, for example, of the type disclosed in the aforementioned copending application.

Referring particularly to FIGURES 1, 3, 6 and 7, to the left of the autoclave 10, as viewed in FIGURE 1, are a plurality of upright laterally spaced bents 28 which carry a stationary load-unload double track section, generally designated 30. The section 30 includes a pair of horizontally extending base plates 32. Longitudinally spaced along each plate 32 are pairs of laterally spaced brackets 34. The brackets on each side of the plate 32 are tied together by a horizontally extending vertically disposed plate 36. Mounted upon the brackets 34 on each side of the plate 32 is a horizontally disposed track bar 38.

Referring particularly to FIGURES 1, 2 and 3, to the right of the autoclave 10 are a pair of upright laterally spaced bents 40 which carry a stationary transfer double track section, generally designated 42. The section 42 includes a pair of horizontally extending base plates 44. Longitudinally spaced along each base plate 44 are pairs of brackets 46. The brackets on each side of the plate 44 are tied together by horizontally extending vertically disposed tie plate 48. Mounted upon the brackets 46 on each side of plate 44 is a horizontally disposed track bar 50.

Referring particularly to FIGURES 2 to 5 and 11, carried by the door 12 is a movable inner track section 51 including a pair of laterally spaced brackets 52, the ends of which carry rollers 54 supported on track bars 56. Intermediate the brackets 52 is a bracket 58. Overlying the brackets 52 and 58 are a set of spacer bars 60 which carry a set of four track bars 62.

Referring particularly to FIGURES 2 to 5 and 14, also carried by the door 12 is a movable outer track section

63 including a pair of laterally spaced brackets 64, the ends of which carry rollers 66 supported on track bars 68. Intermediate the brackets 64 is a bracket 70. Overlying the brackets 64 and 70 are a set of spacer bars 72 which carry four track bars 74. The forward ends of the track bars 68 are carried by adjustable studs 75 which in turn are carried by a framework 76. The framework 76 also mounts a pair of adjustable studs 77 for a purpose to appear.

Referring particularly to FIGURES 1 through 5, extending upwardly from the forward extremities of the brackets 64 is a wall 78 and extending horizontally rearwardly to the door 12 from the top of the wall 78 is a wall 80. The opposite side openings defined by the walls 78 and 80 and the door 12 are closed by a pair of doors 82, the upper end portions of which are tied together by a pair of rods 83. The doors 82 are suspended from rollers 84 which travel on forwardly and upwardly inclined track bars 86. Each track bar 86 is supported at its rear end on the top of the autoclave, as at 88, and is supported at its forward end on a cross member 92 of the framework 76, as at 90, the member 92 being carried by standards 94. Thus the walls 78 and 80, the door 12 and the doors 82 define an auxiliary chamber 95. The wall 78 mounts a compartment 96 in which are located a battery of lamps 98. Above the compartment 96 is mounted a blower 99 for forcing air through the compartment 96, over the lamps 98 and through openings 100 in the wall 78 into the chamber 95. Extending rearwardly from the cross member 92 is a bracket 102 which carries a pivot 104 for a latch 106. The bracket also carries a solenoid 108 for controlling the latch 106.

Referring particularly to FIGURES 1, 3, 6, 7, 11 and 14, mounted upon the stationary load-unload track section 30, movable inner track section 51 and movable outer track section 63, respectively, are identical expandible carriages, generally designated 110, 112 and 114. These carriages are of articulated cross-link construction. Each carriage is provided with guide rollers 116 which travel between and are guided by the associated track bars. At opposite ends of the carriage, respectively, are crossbars 118 and 120. The carriage mounts a battery of vertically extending conventional work supporting forms 121. Underlying the crossbar 120 is a disc 122, the undersurface of which is provided with a depression 124. Underlying the crossbar 118 is a disc 126 from which a pin 128 extends through the crossbar 118. Fitted over the pin 128 is a collar 130 and a collar 132. The collar 132 is provided with axially extending, circumferentially spaced grooves 134. The undersurface of the disc 126 is provided with a recess 136, and extending radially outwardly from the disc 126 are a pair of circumferentially spaced lugs 138 and 140. The crossbar 118 mounts a housing 142 which carries a spring pressed pin 144, the end of which engages in one of the grooves 134. Pivoted to one of the articulated links of the carriage, as at 146, is a latch bar 148 which has at one end thereof a hook 150 which is adapted to engage over a lug 152 mounted on another of the articulated links. Proximate the hook 150 is a lateral projection 154 for coaction with a latch lift 156 carried by a bracket 158 affixed to the movable outer track section 63. Each of the crossbars 118 and 120 carries at opposite ends thereof a guide plate 160, tapered, as at 162.

Referring particularly to FIGURES 1, 2, 6, 7, 8, 11, 12, 14 and 17, a pin 164 extends upwardly into the recess 136 formed in the underside of the disc 126. The pin 164 is carried by a chain 166 trained over a chain sprocket 168 mounted upon a shaft 170 opposite end portions of which are journaled in the associated bent 28. The chain 166 is also trained over a chain sprocket 172 mounted upon a shaft 174 having opposite end portions journaled in the associated bent 28. The chain also carries rollers 175 which overlie a runner 177 extending from the proximate tie plate 36 to prevent the chain from sagging. Also mounted upon the shaft 174 is a chain sprocket 176 over

which is trained a chain 178. The chain 178 is also trained over a chain sprocket 180 mounted upon a shaft 181 opposite end portions of which are journaled in the associated bent 40. Also mounted upon the shaft 181 is a chain sprocket 182 over which is trained a chain 184. The chain 184 is also trained over a chain sprocket 186 mounted upon a shaft 192 having opposite end portions journaled in the associated bent 40 and actuated through a speed reducer 194 by a reversible motor 196. Carried by the chain 184 is a housing 188 which mounts a spring pressed pin 190 that engages in the depression 124 formed in the undersurface of the disc 122. The arrangement is such that the chain 166 moves approximately three times as fast as the chain 184.

Referring to FIGURES 1 to 3 and particularly to FIGURE 19, the carriages 110, 112 and 114 are shown respectively mounted upon track sections 30, 51 and 63 with the full battery of forms carried by each carriage loaded with stockings. The main treatment chamber 10 is closed and the auxiliary chamber 95 is closed. The carriage 110 is in expanded condition for convenient loading and unloading. Carriages 112 and 114 are shown collapsed, the carriage 112 being shown latched against expanding and the carriage 114 being shown collapsed but unlatched. The stockings are treated with fluid media in the chamber 10 and, if desired, may even be partially or completely dried there. If the stockings are not completely dry when they leave chamber 10, the drying operation will be completed in the auxiliary chamber 95. For this purpose a lug 198 carried by the chain 184 operates a switch 200 to close the circuit to the lamps 98 and blower 99. Thus, treatment with fluid media in chamber 10 and drying in chamber 95 go on simultaneously while the carriage 110 is being loaded or unloaded.

When treatment in chamber 10 and drying in chamber 95 are completed, the door 12 moves bodily forwardly from the chamber 10 from the position of FIGURE 10 to that of FIGURES 4 and 20. Thus the chamber 10 is opened. At the same time, the door 12 carries the track sections 51 and 63 and the carriages 112 and 114 mounted thereon forwardly with it. The door 12 also carries the front wall 78 and the top wall 80 forwardly and pushes the doors 82 along the track bars 86. Thus the auxiliary chamber 95 remains closed, and drying continues after the door 12 opens.

As the door 12 approaches its foremost position, a switch 202 is operated thereby, whereupon motor 196 operates. Lug 198 moves clockwise (as viewed in FIGURE 1) about shaft 181, releasing switch 200, whereupon the circuit to lamps 98 and blower 99 is opened. In the meantime, pin 190 moves clockwise about shaft 181, engaging in depression 124 and then moving to the right, pulling carriage 112 onto transfer track section 42. Carriage 112 remains latched against expansion. At the same time, pin 164 moves to the right bearing against one side wall of the recess 136 to push carriage 110. The carriage first collapses and is then pushed onto the inner track section 51. When the carriage collapses, the hook 150 engages over the lug 152 and latches the carriage against expansion. Near the end of the traverse of carriage 110, the lug 138 strikes a lug 203 affixed to the track section 51 and turns the disc 126 so that its recess 136 faces to the right. Thus pin 164 may disengage from the disc as it moves clockwise about the shaft 174. At the same time, the detent 144 disengages from one groove 134 and engages in the other for accurate positioning of the disc 126. At the end of the traverse of carriage 112, the lug 198 (in its dotted line position shown in FIGURE 1) operates a switch (not shown) which opens the motor circuit, whereupon the carriages are arrested in the positions thereof shown in FIGURE 21.

Door 12 now moves bodily back to its closed position and carries track sections 51 and 63 and carriages 110 and 114 with it, the carriage 114 being guided by en-

gagement of the plates 160 with the studs 77. At the same time, door 12 carries front wall 78 and top wall 80 back to the initial positions thereof, but the doors 82 remain in their forward positions, being held by latch 106. This condition of the apparatus is shown in FIGURES 5 and 22.

As the door 12 approaches its fully closed position, a switch 204 is operated, whereupon the circuit to motor 196 is closed, whereupon pin 164 moves back to the left, pulling carriage 114 onto track section 30 and expanding the same for convenient loading and unloading. At the end of the traverse of carriage 114, lug 140 engages a trip 208 and turns the disc 126 to its initial position. Pin 190 moves back to the left pushing carriage 112 onto track section 63, whereupon the projection 154 rides over latch lift 156 to raise the hook 150 from the lug 152 to unlatch the carriage. In the meantime, treatment of the stockings mounted on the battery of forms carried by the carriage 110 commences in chamber 10.

At the end of the traverse of the carriage 112, the lug 198 re-engages and operates switch 200 and a switch 206, whereupon the circuit to the lamps and the blower is closed and the circuit to the motor is opened. At the same time, the solenoid 198 is energized, whereupon the latch 106 is raised and the doors 82 released for return to their initial positions under the influence of gravity, as shown in FIGURE 19.

It will be understood that each carriage 110, 112 and 114 is advanced progressively from stationary load-unload track section 30 to movable inner track section 51 to stationary transfer track section 42 to movable outer track section 63 and back to stationary load-unload track section 30. Movement of a carriage from track section 30 to track section 51 to track section 42 occurs only when the door 12 is open. Movement from track section 42 to track section 63 to track section 30 occurs only when the door 12 is closed. Loading, unloading and re-loading occur when a carriage is on the stationary track section 30 in expanded condition.

It will be understood, of course, that the present invention, as described and shown, is susceptible to various changes and modifications which may be made without any departure from the general principles or real spirit of the invention. For example, instead of heating lamps 98, other heating means may be substituted. In this connection, the heating means may be located elsewhere, for example, instead of being located high on the wall 78, the heating lamps 98 may be located low on the wall 78, and instead of being located over the compartment 96, the blower 99 may be mounted under the compartment 96. Accordingly, it is intended to claim the present invention broadly, as well as specifically, as indicated in the appended claims.

What is claimed is:

1. In apparatus for treating textiles, the combination comprising means providing a main treatment chamber closed by a door in the front thereof movable bodily outwardly from the chamber, track means extending along the front of said door including longitudinally spaced stationary load-unload and transfer track sections respectively on opposite sides of the chamber, and track sections mounted respectively upon the inner and outer sides of said door for movement therewith, said outer movable track section being interposed between and aligned with said stationary track sections, and said inner movable track section being adapted for being interposed between and aligned with said stationary track sections when said door is open, means coacting with said door to provide an auxiliary chamber over said outer movable track section, carriages for supporting textile materials to be treated, said carriages being respectively mounted upon said stationary load-unload and movable inner and outer track sections, and means for opening and closing said chambers and actuating said carriages in predetermined timed relation whereby each carriage is progressively advanced from said stationary load-unload track section

successively to the other track sections and then back to said stationary load-unload track sections for treatment of the textile materials first in said main treatment chamber and then in said auxiliary chamber.

5 2. In apparatus for treating textiles, the combination as defined in claim 1 wherein the means coacting with the door to provide an auxiliary chamber includes a framework covering the movable outer track section and mounted upon said door for movement therewith, and a pair of doors closing openings respectively on opposite sides of said framework and operable for opening said auxiliary chamber for passage of said carriages into and out of the same through said openings.

10 3. In apparatus for treating textiles, the combination as defined in claim 2 wherein the pair of doors closing the openings respectively on opposite sides of the framework of the auxiliary chamber are mounted for substantially planar shifting movement outwardly from the main treatment chamber for opening the auxiliary chamber, said pairs of doors being operative in the outwardly shifted position thereof for closing said auxiliary treatment chamber when the framework of the latter is moved outwardly by the door of said main treatment chamber.

15 4. In apparatus for treating textiles, the combination as defined in claim 2 wherein the doors of said auxiliary chamber are automatically shifted outwardly from the main treatment chamber when the latter opens, and the means for opening and closing said chamber and actuating the carriages in predetermined timed relation includes means for automatically arresting positively the doors of said auxiliary chamber in their outwardly shifted position for a predetermined time interval and then automatically releasing them for return to their initial positions.

20 35 5. In apparatus for treating textiles, the combination as defined in claim 3 wherein the doors of said auxiliary chamber are automatically opened by the door of said main treatment chamber against the influence of gravity when the latter opens, and the means for opening and closing said chambers and actuating the carriages in predetermined timed relation includes means for automatically arresting positively the doors of said auxiliary chamber in their outwardly shifted position for a predetermined time interval and then automatically releasing them for return to their initial positions under the influence of gravity.

25 6. In apparatus for treating textiles, the combination comprising means providing a main treatment chamber closed by an upright door in the front thereof movable bodily outwardly from the chamber to an upright position substantially parallel to the initial closed position thereof, track means extending horizontally along the front of said door including longitudinally spaced stationary load-unload and transfer track sections respectively on opposite sides of the chamber, and track sections mounted respectively upon the inner and outer sides of said door for movement therewith, said outer movable track section being interposed between and aligned with said stationary track sections, and said inner movable track section being adapted for being interposed between and aligned with said stationary track sections when said door is open, means coacting with said door to provide an auxiliary chamber over said outer movable track section, carriages for supporting textile materials to be treated, said carriages being respectively mounted upon said stationary load-unload and movable inner and outer track sections, means for opening and closing said chambers and actuating said carriages in predetermined timed relation whereby each carriage is progressively advanced from said stationary load-unload track section successively to the other track sections and then back to said stationary load-unload track section, and means for treating the textile material in said main treatment chamber and then drying the same in said auxiliary chamber.

30 7. In apparatus for treating textiles, the combination

comprising means providing a main treatment chamber closed by a door in the front thereof movable bodily outwardly from the chamber, track means extending along the front of said door including longitudinally spaced stationary load-unload and transfer track sections respectively on opposite sides of the chamber, and track sections mounted respectively upon the inner and outer sides of said door for movement therewith, said outer movable track section being interposed between and aligned with said stationary track sections, and said inner movable track section being adapted for being interposed between and aligned with said stationary track sections when said door is open, means coacting with said door to provide an auxiliary chamber over said outer movable track section, carriages for supporting textile materials to be treated, said carriages being respectively mounted upon said stationary load-unload and movable inner and outer track sections, and means for opening and closing said chambers and actuating said carriages in predetermined timed relation including reciprocable means associated with said stationary track sections and coacting with the door of said main treatment chamber to shift said carriages from said stationary load-unload track section successively to said movable inner track section, said stationary transfer track section, said movable outer track section and then back to said stationary load-unload track section for treatment of the textile materials first in said main treatment chamber and then in said auxiliary chamber.

8. In apparatus for treating textiles, the combination comprising means providing a main treatment chamber closed by a door in the front thereof movable bodily outwardly from the chamber, track means extending along the front of said door including longitudinally spaced stationary load-unload and transfer track sections respectively on opposite sides of the chamber, and track sections mounted respectively upon the inner and outer sides of said door for movement therewith, said outer movable track section being interposed between and aligned with said stationary track sections, and said inner movable track section being adapted for being interposed between and aligned with said stationary track sections when said door is open, means coacting with said door to provide an auxiliary chamber over said outer movable track section, expandable carriages for supporting textile materials to be treated, said carriages being respectively mounted upon said stationary load-unload and movable inner and outer track sections, means for opening and closing said chambers and actuating said carriages in predetermined timed relation including means associated with said stationary track sections and coacting with the door of said main treatment chamber to shift said carriages from said stationary load-unload track section successively to said movable inner track section, said stationary transfer track section, said movable outer track section and then back to said stationary load-unload track section for treatment of the textile materials first in said main treatment chamber and then in said auxiliary chamber, and means for latching each of said carriages against expansion as it enters upon said movable inner track section and for unlatching the carriage as it enters upon said movable outer track section.

9. In apparatus for treating textiles, the combination comprising means providing a main treatment chamber closed by a door in the front thereof movable bodily outwardly from the chamber, track means extending along the front of said door including longitudinally spaced stationary load-unload and transfer track sections respectively on opposite sides of the chamber, and track sections mounted respectively upon the inner and outer sides of said door for movement therewith, said outer movable track section being interposed between and aligned with

5 said stationary track sections, and said inner movable track section being adapted for being interposed between and aligned with said stationary track sections when said door is open, means coacting with said door to provide an auxiliary chamber over said outer movable track section, expandable carriages for supporting textile materials to be treated, one of said carriages being mounted upon said stationary load-unload track section in expanded condition and other carriages being mounted respectively upon said movable inner and outer track sections in collapsed condition, and means for opening and closing said chambers and actuating said carriages in predetermined timed relation including reciprocable means associated with said stationary track sections and coacting with the door of said main treatment chamber to shift said carriages from said stationary load-unload track section successively to said movable inner track section, said stationary transfer track section, said movable outer track section and then back to said stationary load-unload track section for treatment of the textile materials first in said main treatment chamber and then in said auxiliary chamber, said reciprocable means being operable for collapsing each of said carriages as it leaves said stationary load-unload track section and expanding each of said carriages as it reenters upon said stationary load-unload track section.

10. In apparatus for treating textiles, the combination comprising means providing a main treatment chamber closed by a door in the front thereof movable bodily outwardly from the chamber, track means extending along the front of said door including longitudinally spaced stationary load-unload and transfer track sections respectively on opposite sides of the chamber, and track sections mounted respectively upon the inner and outer sides of said door for movement therewith, said outer movable track section being interposed between and aligned with said stationary track sections, and said inner movable track section being adapted for being interposed between and aligned with said stationary track sections when said door is open, means coacting with said door to provide an auxiliary chamber over said outer movable track section, expandable carriages for supporting textile materials to be treated, one of said carriages being mounted upon said stationary load-unload track sections in expanded condition and other carriages being mounted respectively upon said movable inner and outer track sections in collapsed condition, and means for opening and closing said chambers and actuating said carriages in predetermined timed relation including reciprocable means associated with said stationary track sections and coacting with the door of said main treatment chamber to shift said carriages from said stationary load-unload track section successively to said movable inner track section, said stationary transfer track section, said movable outer track section and then back to said stationary load-unload track section for treatment of the textile materials first in said main treatment chamber and then in said auxiliary chamber, said reciprocable means being operable for collapsing each of said carriages as it leaves said stationary load-unload track section and expanding each of said carriages as it reenters upon said stationary load-unload track section.
